UNITED STATES PATENT OFFICE.

JOHN ALPHEUS CAMPBELL, OF CARBONDALE, ILLINOIS.

STAMPING DEVICE.

1,420,686.

Specification of Letters Patent. Patented June 27, 1922.

Application filed April 8, 1921. Serial No. 459,589.

To all whom it may concern:

Be it known that I, JOHN A. CAMPBELL, a citizen of the United States, and a resident of Carbondale, in the county of Jackson and State of Illinois, have invented a new and Improved Stamping Device, of which the following is a description.

My invention relates to a stamping device which while having wider use is more particularly designed for marking an automobile in various places such as on the fender, hood, apron, body, cowl, bows, and other different parts by stamping on the parts identifying letters, symbols, or other marks, such for example as the initials of the owner and the abbreviation of the State in which the automobile is licensed, the purpose being to make difficult the obliteration of the marks by thieves.

20 The general object of the invention is to provide a tool for the indicated purpose which may be readily applied to the part to be marked, and operated with facility to impress the mark.

25 The distinctive features of the invention and its advantages will clearly appear as the description proceeds.

Reference is to be had to the accompanying drawings forming a part of this specification, it being understood that the drawings are merely illustrative of one example of the invention.

Figure 1 is a side elevation of a stamping device embodying my invention, portions of the handle being broken away;

Figure 2 is a section on the line 2—2, Figure 1;

Figure 3 is a perspective view of the stamp, shown partly broken away and in section;

Figure 4 is a perspective view of one of the stamping blocks.

In carrying out my invention in accordance with the illustrated example, the head 10 is provided having a handle 11. Adjustable longitudinally in the head 10 is a shank 12, the front end of which is deflected laterally as at 13 and terminates in an anvil element 14 constituting one member of the clamp, the head 10 as hereinafter described, forming a coacting clamp member. The rear end of the shank extends beyond the head 10 and is threaded to receive a nut 15 for adjusting the anvil

clamping element 14 relatively to the front 55 of the head 10.

On the head 10 at the front is a stamp designated generally by the numeral 16, the base of which has a shank 17 extending rearwardly in the head and having a spring 60 18 coiled about the same, the spring being held at its rear end by a cap 19 screwed on the end or shank, or equivalent holding means for the spring.

For reciprocating the stamp 17 toward the 65 anvil member 14, an operating device 20, constituting a lever, is provided and pivoted near its front end as at 21 to the head 10, the front transversely bevelled surface 22 of said handle 20 being adapted by the 70 rocking of the handle to bear against the shank 18 at its cap 19 to thereby move the stamp 16 forwardly.

With the described arrangement the device is applied to the part of the automobile 75 to be stamped by entering said part between the anvil 14 and the stamp 16 and by adjusting the nut 15 the head 10 with the stamp 16 and the anvil 14 serve to clamp the tool to the material sufficiently tight to 80 position the tool, after which the handle 20 is rocked to cause its front edge 20 to engage the shank of the stamp and force the stamp forwardly impressing its marks or symbols in the material of the automobile part. 85

The spring 18 serves to restore the stamp after a forward movement by the handle 20.

In order that the symbols or marks of the stamps may be changed a holder block 90 23 is provided, the back of which has a dove-tail rib 23^a slidable in a corresponding groove 16^a in the base of the stamp. The front of the holder block 23 is recessed to receive a series of individual stamping 95 blocks or type blocks 24 which are locked in place by a rod 25 extending longitudinally of the block 23 and engaging partly in a concave groove 26 in said block and partly in concave grooves 27 in the stamping 100 blocks 24. On the one end of the rod 25 is a clamp head 28 returned laterally inward to overlap the adjacent face of the holder block 23, the returned end being resilient to give clamping action. 105

I would state in conclusion that while the illustrated example constitutes a practical embodiment of my invention, I do not

limit myself strictly to the mechanical details herein illustrated, since manifestly the same can be considerably varied without departure from the spirit of the invention 5 as defined in the appended claims.

Having thus described my invention, I claim:

1. A device of the class described, including a head having a handle, a stamp 10 having a shank adapted to be reciprocated in said head, an anvil element adjustable on said head and extending laterally in front of the head, a lever pivoted for movement toward or from said handle and formed 15 with a transversely bevelled front end

adapted to engage said shank and move the shank toward the anvil element, and a spring on said shank for restoring the stamp after movement toward the anvil element.

2. In a device of the class described, a stamp including a holder having a recess, separate stamp blocks accommodated in said recess, and a locking rod slidable in the holder and engaging said stamping 25 blocks to retain the same in position, said rod having a returned end approximately parallel with the axis of the rod and adapted to bear against the face of the holder.

JOHN ALPHEUS CAMPBELL.
